SELENIUM RECTIFIER TEMPERATURE INDICATOR

George H. Shoemaker, Brooklyn, N. Y., assignor to
 Federal Telephone & Radio Corporation, New
 York, N. Y., a corporation of Delaware

Application May 1, 1943, Serial No. 485,379

4 Claims. (Cl. 175—366)

This invention relates to means for obtaining an indication of the temperature of a selenium type rectifier and has for its object to provide a convenient indication of the temperature of the selenium rectifier while in use.

As is well known, a selenium rectifier ordinarily comprises a layer of selenium adhering to a base plate or element, and covered by a conductive counter-electrode which is usually provided by spraying a metallic alloy over the selenium surface. There is thus formed on the selenium surface under the counter-electrode a "blocking layer" which is thought to block the current flow in the reverse direction and provide the rectifying action.

Selenium rectifier discs are subject to heating during operation, caused by the resistance offered by the plates themselves to the passage of current. The maximum temperature to which the disc may safely rise is governed by the melting point of the most readily fusible component of the rectifier, which is usually the metallic counter-electrode. It is frequently desirable to measure the temperature of the disc while it is in use to learn how close it is to the maximum safe temperature and therefore whether the input current can be increased. According to my invention I do this by leaving a small area of the selenium layer free of the metallic counter-electrode, to which exposed area of selenium I attach a pyrometer or thermocouple.

By this arrangement there is no injury to the barrier layer beneath the counter-electrode and consequently no danger of short circuit; and by use of the pyrometer or thermocouple an indication of the temperature at a hot part of the element can readily be had.

The invention will be better understood from the following detailed description and the attached drawing of which:

Figure 1 is a cross-section view of a selenium rectifier disc having a small area of exposed selenium surface in contact with the junction of a thermocouple;

Figure 2 is a plan view of the same.

Figure 1 shows the usual type of selenium rectifier disc comprising a base plate 1 which may be of steel serving as a back electrode, and superimposed thereon a coating of crystalline selenium 2 on top of which has been sprayed an alloy serving as the counter-electrode 3. Within the alloyed area, a small area 4 of the selenium is left uncovered by the alloy, and this may conveniently be done by applying a piece of adhesive

tape about $\frac{1}{16}$ " in diameter over this area of selenium layer before spraying. I then spray the alloy on the selenium layer whereupon all but the area protected by the tape receives a coating.

5 When the spraying operation is complete I remove the tape and fuse the junction 5 of a thermocouple to the exposed selenium surface by applying a hot point to the junction and pressing it down into the selenium which softens. The 10 thermocouple may be conveniently made by twisting a copper wire and a constantan wire together (indicated by 6 and 7) and heating the end 5 to conform to the surface of the selenium to which it is fused. The junction is extremely 15 thin and may be somewhat oval in shape. During the fusing care must be taken to see that the junction does not sink deep enough in the selenium layer to contact the base plate beneath the selenium, and care should be taken that no exposed metal of the thermocouple touches the counter-electrode. It may be desirable to spray the thermocouple area lightly over with varnish. An indication of the temperature may be obtained in a well-known manner by connecting a 20 meter such as a galvanometer in circuit with the thermocouple.

I do not wish to be limited to a thermocouple as a means for measuring the temperature, but 25 contemplate the use of any electrical pyrometer such as the platinum resistance pyrometer of similar device for this purpose.

What I claim is:

1. A selenium rectifier element comprising a base plate, a layer of selenium placed over a surface of said base plate, a counter-electrode placed over said selenium layer so as to leave exposed a small area of said selenium layer, and a thermocouple junction fused to the said exposed area of said selenium layer.

2. The method of making a selenium rectifier element which comprises forming a layer of selenium on a base plate, applying a covering over a small area of the surface of said selenium, applying a counter-electrode on said selenium layer and around said covering, removing said covering and fusing a thermocouple to the exposed area of the selenium surface from which the covering was removed.

3. The method of making a selenium rectifier element which comprises forming a layer of selenium on a base plate, applying a covering over a small area of the surface of said selenium, applying a counter-electrode on said selenium layer and around said covering, removing said covering

and fusing an electrical heat responsive device to the exposed area of the selenium surface from which the covering was removed.

4. A selenium rectifier element comprising a base plate, a layer of selenium placed over a surface of said base plate, a counter-electrode placed over said selenium layer so as to leave

exposed a small area of said selenium layer, an electrical heat responsive device embedded in said exposed area of said selenium layer, and a protective insulating layer covering said heat responsive device.

GEORGE H. SHOEMAKER.
